PACKAGING DEVICE

Application filed November 23, 1931. Serial No. 576,800.

My invention relates to means for packaging a plurality of small articles of irregular outline, such as screw hooks, screw eyes and other devices such as are formed from wire, for example, and which, by reason of their awkward shape, do not lend themselves to easy, careful or compact packaging. Ordinarily, such articles are handled in bulk but in modern merchandising such as conducted 10 by the so called "Five and ten cent stores" the call is for a neat and efficient package of such a number of such articles as can be sold for a small coin. To that end I have devised such a package and have shown the same in 15 one preferred form in the accompanying drawing, in which—

Fig. 1 is a side view;

Fig. 2 is an edge view.

In the particular form of my invention 20 that I have elected to show in the drawing the holder is especially shaped to receive and hold in a compact and neat packaging arrangement a dozen screw hooks.

1 represents what I may term a backing 25 member. The upper end of this backing member is provided with a transverse slot to form two spaced holding shoulders 2—2. 3—3 represent cheek pieces at the opposite side edges of said backing member, which 30 cheeks extend back at an angle thereto for the double purpose of reinforcing the backing against bending and of forming a pocket for the articles to be assembled side by side. In the present instance the holder is adapted 35 to receive a plurality of screw hooks 4—4, the hook ends of which may be passed through the slot forming the shoulders 2—2. The shanks of said hooks are then placed side by side in the space or pocket between 40 the cheek pieces. 5 represents a strap, which may overlie the shanks of the hooks to hold them in said pocket and against the backing. If desired shoulders 6 may be formed on the 45 edges of the cheek pieces, to prevent accidental slipping off of the strap, and these shoulders may be easily formed by merely notching the extreme edge of each cheek piece. When the articles are assembled as 50 shown they occupy a minimum of space, since they rest against each other side by side,

the end hooks being supported by the aforesaid cheek pieces and the shanks of all of the hooks being held by the backing between the cheek pieces. The construction permits very quick packaging and, by reason of its great 55 compactness and the security with which the articles are held, permits ready and economical transportation.

What I claim is:

A holder for the packaging of a plurality 60 of irregularly shaped articles, comprising a backing member, perforated adjacent one end edge to form holding shoulders to receive between them the irregular end portions of a plurality of irregularly shaped articles, with 65 means to hold the other portions of said articles against the rear of said backing, with cheek pieces at the side edges of said backing to reinforce the latter and to form a holding pocket for the last mentioned parts of said 70 articles.

OSCAR N. WHITEHEAD.
